UNITED STATES PATENT OFFICE.

ALBERT HENRY MIDGLEY AND CHARLES ANTHONY VANDERVELL, OF ACTON VALE,
ENGLAND.

DYNAMO-ELECTRIC MACHINE, PARTICULARLY APPLICABLE FOR IGNITION PURPOSES
IN CONNECTION WITH INTERNAL-COMBUSTION ENGINES.

1,068,152.

Specification of Letters Patent.

Patented July 22, 1913.

Application filed December 6, 1910. Serial No. 595,952.

To all whom it may concern:

Be it known that we, ALBERT HENRY MIDGLEY and CHARLES ANTHONY VANDERVELL, subjects of the King of Great Britain and Ireland, residing at Warple Way, Acton Vale, in the county of Middlesex, England, have invented new and useful improvements in and relating to dynamo-electric machines particularly applicable for ignition purposes in connection with internal-combustion engines, of which the following is a specification.

This invention relates to an electric ignition system employing direct current for use in connection with internal combustion engines and has for its object the provision of means whereby the source of current for ignition purposes can be used as a source of current for lighting purposes also.

20 In connection with internal combustion engines for driving motor-cars, motor-boats, and the like, it has been customary to utilize either one of two systems namely, a high tension system or a low tension system. 25 With a high tension system depending for its electric energy on secondary batteries so long as the batteries are of large capacity a lighting circuit can be installed in addition to the ignition circuit, but owing to the variable speed of the internal combustion engine it has been impossible up to the present to utilize a dynamo driven thereby without complicated cut-out devices. In systems in which a magneto generator is used, such 30 generator cannot be utilized for the purpose of charging the battery owing to the great variation in voltage due to the wide range of speed through which the prime mover operates, consequently great complexity of apparatus or great weight of plant is involved where electric ignition and electric lighting are to be installed on the same vehicle or boat. Our invention overcomes all these difficulties and enables the combined effect 45 to be carried out by the use of one generator with the distributing device attached thereto, so that only a single driving connection has to be made between the dynamo and the internal combustion engine.

50 To carry our invention into effect, we take a variable speed constant voltage dynamo preferably of the type described in the application for United States Patent Serial No. 571351 of the 11th of July 1910 and on

the shaft of the same we mount direct, a distributor having the proper number of contacts for the multi-cylinder internal combustion engine with which the device has to work. In conjunction or equivalently we may mount the distributor upon an independent axis and drive it by means of suitable gearing from the armature. In connection with the armature we also arrange a make and break contact device adapted to give time variation in the period of the passage of the current in order to advance or retard the spark at the firing plugs. This dynamo is connected to the mains for charging the secondary battery from which the current for lighting purposes is derived and is also connected with the usual electrical devices such as condenser, induction coil or other transforming device and the high or low tension firing plugs of the ordinary form and arrangement utilized in known systems at the present time and the field coils of the dynamo are also connected across the secondary battery in order to maintain the current exciting the field magnets at a constant voltage so as to insure constant current from the dynamo to be fed to the battery.

It will be seen that by the use of a self-contained variable speed constant voltage dynamo with distributor and contact breaker all the other apparatus such as magnetos or independent secondary batteries are entirely eliminated from the installation of electrical appliances for car work with all the difficulties consequent thereon.

In order that the invention may be the better understood, we will now proceed to describe the same, in relation to the accompanying drawing, reference being had to the letters and figures marked thereon.

Like letters refer to like parts in the various figures.

Figure 1 is a sectional view of a dynamo constructed in accordance with our invention. Fig. 2 is a diagrammatic representation of the various devices and electrical connections for low tension ignition. Fig. 3 is a similar diagrammatic representation for high tension ignition.

Referring to Fig. 1 in which we illustrate a dynamo arranged for a four cylinder internal combustion engine, the armature *a* is directly geared to the shaft *b* of the internal

combustion engine by means of equal gear *c* and the usual commutator *d* and brushes *e* are provided for collecting the current from the armature *a*. At the right hand end of the machine a make and break device *f* is arranged, the timing operation of which in relation to the engine is effected by rocking the casing *g* about its axis by means of the lever *h* in the usual manner. At the left hand end of the machine a distributer *j* is provided having the same number of contacts as there are cylinders to the engine. The brush *k* of the distributer is rotated by means of spur gearing *l* from the shaft of the armature *a*; such gearing in the present instance being in the ratio of 1 to 2.

In Fig. 2 the arrangement of the various parts relative to the electric circuits connecting them is clearly indicated. In this case the firing plugs *m* are of a mechanical type electrically operated. The battery *n* is placed across the mains as are also the various lamps *o* of the lighting installation. *p p* represent the coils of the field magnets of the machine which are connected up across the terminals of the battery for the purpose hereinbefore described, and *q* represents the condenser placed in the circuit in the usual manner. In Fig. 3 similar arrangements are diagrammatically illustrated for the ordinary high tension ignition plugs, the only difference being a small variation in the circuit in order to deal with the high tension and low tension currents. In this case also the field magnets are connected across the terminals of the battery for the purpose hereinbefore described.

Having thus fully described our invention we claim as new and desire to secure by Letters Patent:—

1. An ignition system comprising a direct current dynamo having a field magnet sys-

tem having coils connected across the mains, an armature adapted to give a constant voltage at variable speed, a commutator on said armature, brushes positively associated with said commutator conducting mains connected to said brushes, a storage battery connected across the mains and adapted to be charged with current from said armature in combination with a distributer driven positively from said armature adapted to distribute current from said armature to act on the ignition device of each cylinder of an internal combustion engine and a make and break device driven positively from said armature for controlling the current from said distributer, substantially as described.

2. In purposes of the class described, in combination, a constant direct current generator provided with an armature adapted to be driven by an internal combustion engine, an ignition device for the engine, a distributer positively driven by said armature to distribute current to the ignition device, a make and break device driven positively by said armature to control the current from said distributer, said armature being provided with a commutator, brushes positively associated with said commutator, conducting mains connected to said brushes, a field magnet system having coils connected across said mains and a storage battery connected across said mains and adapted to be charged with current from said generator substantially as described.

In testimony whereof we have signed our names to this specification in the presence of two subscribing witnesses.

ALBERT HENRY MIDGLEY.

CHARLES ANTHONY VANDERVELL.
